UNITED STATES PATENT OFFICE.

WILSON L. POTTER, OF HARTFORD, CONNECTICUT.

BELT-FASTENING.

SPECIFICATION forming part of Letters Patent No. 270,117, dated January 2, 1883.

Application filed October 26, 1882. (No model.)

To all whom it may concern:

Be it known that I, WILSON L. POTTER, a citizen of the United States, residing at Hartford, in the county of Hartford and State of Connecticut, have invented new and useful Improvements in Belt-Fastenings, of which the following is a specification.

This invention relates to an improved belt-fastening more especially adapted for use upon the class of rubber and canvas belts; and it consists of the combination, with the contiguous ends of a belt, of a metallic plate provided with one or more rows of spurs arranged to come opposite each end of the belt. The spurs are adapted to be forced through the belt, and to have their ends clinched by being bent down diagonally to have their points extend toward the contiguous ends of the belt. The spurs are malleable and of a true conical form, as shown, to enable them to penetrate the belt without rupturing or cutting the threads of its fabric.

In the drawings, Figure I is a plan view of the fastener secured to one end of a belt. Fig. II is an end view of the same, and Fig. III is a plan view of the fastener as combined with a belt.

A is a metallic plate provided upon one face with the spurs b b b. The spurs b are arranged in one or more transverse rows, and when more than one row is provided to come opposite one of contiguous belt ends the rows are arranged, as seen in the drawings, to have one spur come opposite the interval between the spurs of the adjacent row. The spurs b are of configuration as seen in profile, Fig. II,

and, being conical, would present the same appearance in any elevation. This gradual cone-surface enables the spurs to be driven through the belt without injury to any fabric forming part of it. When the plate A is laid over the contiguous ends B B of a belt and the spurs b forced through the belt the fastening is completed by clinching each projecting spur end; and it is essential in forming my improved fastening that each end should be turned down diagonally and to oppose the ends of those contained in the opposite belt end, by means of which the greatest opposition is brought against all strain in either a longitudinal or transverse direction. The round cross-section of the spurs b not only prevents injury to the cloth, but enables its end to be clinched in this diagonal direction.

In Fig. III the turned-down ends of a plate-fastener are shown, and it will be seen from the position of these turned-down ends that a large resistance is offered to strain in either direction.

Now, having described my invention, what I claim is—

The combination, with the contiguous ends of a belt, B, of the plate A, provided with the conical malleable spurs b, arranged in rows relatively, as shown, and adapted to unite the plate A to the belt B by having their ends clinched by being bent diagonally toward the end of the belt, as set forth.

WILSON L. POTTER.
